UNITED STATES PATENT OFFICE

KARL F. NYSTROM, OF MILWAUKEE, WISCONSIN

RETAINER VALVE FASTENING

Application filed November 18, 1929. Serial No. 408,150.

My invention relates to a method of securing the retaining valve of the air brake operating mechanism to a railroad freight car; the invention contemplating simple means for securing the retaining valve to the car at a point where the valve is easily accessible to the trainman, namely in position where the top of the retainer valve is approximately in line with the usual running board on the roof of the car and therefore at a point where the operating lever of the retainer valve is so positioned as to be in easy reach from the trainman's position on the running board while at the same time in close proximity to the trainman when stationed on the usual brake step at the end of the car.

It is essential that the retaining valve and its lever be so placed as to permit easy operation thereof for the purpose of controlling movement of a train and therefore the valve and its lever must be within easy reach while the trainman is on the car so as to enable the trainman, within a comparatively short space of time, to run along the tops of the cars of a train and operate the various valve-levers.

My invention also has for its object the provision of means which will obviate use of the more expensive anchors or brackets and also whereby the necessity of drilling bolt receiving holes through the end walls of the car will be eliminated; the latter method making access to the bolts, should occasion require when the car is loaded and the doors of the car sealed, impracticable.

The objects and advantages of my invention will be readily comprehended from the following detailed description of the accompanying drawings, wherein:

Figure 1 is a top plan view of one end of a freight car and its running-boards, with the retainer valve secured in place.

Figure 2 is an end elevation of a portion of the top of the freight car.

Figure 3 is a horizontal sectional view taken substantially on the line 3-3 of Figure 2.

In the particular exemplification of the invention, a portion of the upper end wall of a freight car is shown at 10, provided with the

usual oppositely sloping roof 11; while the car at the crown or ridge of the roof is provided with the usual running-board, a portion whereof is shown at 12 disposed lengthwise of the car from end to end. These running-boards usually consist of the parallelly arranged and slightly spaced planks or boards as shown which are supported by saddles arranged at predetermined distances apart and disposed transversely of the ridge of the roof. The usual type of running-board saddle is shown at 13 in Figure 1; being arranged transversely of the roof, with the bottom of the saddle, which is usually of wood, cut in an oppositely sloping manner to receive the crown or ridge of the roof at the juncture of the oppositely sloping bottom sides; the saddles being suitably secured to the roof timbers of the car.

The usual saddles are of length commensurate with the width of the composite running boards which usually consists of three parallelly arranged spaced planks 14, as shown in Figure 1; so that the ends of the saddles are arranged substantially flush with the outer longitudinal edges of the outer planks or boards 14, as shown at 13 in Figure 1.

My invention contemplates providing an end saddle, namely the running board saddle at the ends of the car, with an extended portion as shown at 15 in Figures 1 and 2 and arranged to have the extended portion disposed beyond one of the longitudinal sides of the composite running board 12.

In the particular exemplification of the invention, the extension 15 preferably consists of an integral portion of the end saddle whose bottom is formed in the opposite sloping manner to receive or match the crown or ridge of the roof; the entire bottom of the extended side of the saddle being cut or formed at an angle matching the slope of the roof, as shown at 16 in Figure 2, in order that the saddle with its extension may present an upper horizontal face to receive the ends of the running boards as shown, and also to provide an exposed portion of the saddle disposed substantially flush with the end of the car for the purpose of providing

means for supporting the usual air-brake system retaining valve indicated at 17.

The pressure-retaining valve 17 is threaded or attached to the upper end of a pipe, a portion of which is shown at 18 in Figure 2, which communicates with the triple valve, not shown, of the air brake system. The pressure retaining valve 17, which is of a well known construction, involves a body casting provided with oppositely disposed and aligned integral securing ears or lobes 19, 19, which are apertured to receive securing bolts.

Heretofore, retaining valves have been secured to the end walls of a freight car by means of anchors or brackets which in turn are bolted to the car end walls, with the bolts of the bracket disposed through the car wall. Aside from the expense of such brackets, such fastening means involve the drilling of holes through the end wall of the car for the purpose of receiving the bracket retaining bolts whose fastening nuts are usually located on the car interior.

In the event of wear of the bolt-holes or a loosening of the nuts through the turning of the bolts, it was necessary to have access to the car interior for the purpose of screwing up the nuts. Where the car was loaded, access to the nuts within the car was impossible without removing the load. This not only meant a loss of time, but at times was not feasible because it required a breaking of the car-seal, which is not desirable.

The purpose of my invention is to provide a method of fastening the retaining valve which will eliminate the difficulties above mentioned and which at the same time will position the retaining valve at a more accessible point for operation by the trainman so as to enable quick operation of the retaining valve levers on the various cars of a train without need for the trainman to descend from the running board or to assume a dangerous position for operation which might result in his losing his balance during movement of the cars.

As shown in the drawings, the extended portion 15 of the end saddle provides means for mounting the retaining valve 17 which is accomplished through the use of a pair of suitable bolts 20, 20 of length sufficient to extend through two holes drilled transversely of the extension 15, at spaced apart points, adapted to register with the usual apertures in the lobes or ears 19, 19 of the retaining valve, as shown in Figure 3.

As the lobes 19, 19 of the retaining valve are usually rather short and in close proximity to the body of the retaining valve and therefore do not provide a great amount of clearance for the reception of a wrench, the bolts 20, 20 are usually inserted through the ears or lobes and thence through the holes in the extension 15 of the end saddle so that the

nuts 21 may be screwed onto the ends of the bolts at the opposite inner face of the extension 15 of the end saddle, as shown in Figures 1 and 3.

As the saddles are usually made of wood, with the extension 15 preferably integral therewith, I prefer to provide means in the nature of a metallic plate 22, Figure 3, apertured for passage of the ends of the bolts 20, 20 therethrough, in order that the nuts 21 when screwed up tightly into place cannot cut or be countersunk into the wood. At the same time, the plate 22, which is preferably made of steel, has its ends extend sufficiently beyond the bolt-receiving apertures to permit the ends of the plates after the nuts have been firmly screwed into place, to be bent upwardly against the sides of the nuts as shown at 23, 23 in Figure 3, to provide means for locking the nuts against rotation.

As is apparent from Figure 2, the retaining valve 17 is arranged approximately in line with the running-board so that the valve-handle 24 is positioned where it can be easily reached by the trainman while on the running-board of the car, with the result that operation of the retaining valves on the different cars of a train may be accomplished in a comparatively short space of time.

I have illustrated my invention in connection with a running-board saddle and an integral extension composed of wood (material usually employed), but it is apparent that the saddle and the extension may be of metal and that the extension 15 need not necessarily be made an integral part of the end saddle, but may be secured thereto or arranged in longitudinal alignment therewith in order that the retaining valve receiving face of the extension is disposed substantially in vertical alignment with the end wall of the car and with the retaining valve approximately in the plane of the roof.

I have shown what I believe to be the simplest embodiment of my invention adapted to present freight car construction and have described the invention in terms which are employed merely as terms of description and not as terms of limitation, as modifications are possible without, however, departing from the spirit of my invention.

What I claim is:

1. In combination with the retainer valve of an air brake system and the running-board saddle of a freight car, bolt receiving means arranged at one end of the saddle of a freight car and disposed beyond one side of the running board, said means being arranged substantially in the plane of the end wall of the car and adapted to have the retaining valve secured thereto.

2. In combination with the retainer valve of an air brake system, a freight car running-board end saddle secured on the roof of the car, said saddle being of length greater than

the width of the running-board with one end of the saddle disposed beyond one longitudinal side of the running-board, and means for securing the retaining valve to the outer vertical face of said extended portion of the end saddle.

5 3. In combination with the retainer valve of an air brake system, a freight car running-board end saddle secured on the roof of the car, said saddle having an extension at one end disposed beyond one longitudinal side of the running board, bolts for securing the retaining valve to the vertical face of said extension, and means arranged on the opposite vertical face of said extension for holding the nuts of the bolts against rotation.
